UNITED STATES PATENT OFFICE

2,577,323

BUILDING WALL CONSTRUCTION

Eugene Goenner, Woodside, N. Y.

Application October 16, 1946, Serial No. 703,661

3 Claims. (Cl. 72—16)

1

This invention relates to building construction and parts therefor, and has for an object the provision of a building that can be easily constructed by unskilled labor, as the majority of parts are prefabricated and can be made in standard units which are easily put together on the building site with a minimum of labor and expense.

Another object is the provision of a building construction wherein the framing is of columnar construction wherein the columns may be standard 2" steel pipe or the like, and where the frame can be put together without threading or joints that require any metal working on the job.

Another object is to provide a building construction in which preformed panels are employed which are placed between columns and locked securely in place by locking means extending between the panels and the columns as hereinafter described.

Another object is the provision of a building construction of the type described wherein panels are secured to the columns by means extending between the panels and the columns and into the interior of the latter, said means being locked in position by filling the columns with a pourable material such as concrete or the like.

A further object is the provision of a preformed panel for use in building construction which has a central membrane, preferably of waterproof material, whereby the efficiency of the panel as a wall is increased and the penetration of moisture through the panel is prevented.

Other objects and advantages will be apparent from the following specification taken together with the accompanying drawings, in which a preferred embodiment of the invention is disclosed by way of illustration. It will be understood, however, that many changes and departures can be made in the details of construction herein set forth, the invention being as defined in the appended claims.

Referring to the accompanying drawings:

Figure 1 is an isometric view of a building embodying the invention.

Figure 2 is a transverse sectional view of one of the columns and adjacent panels shown in Figure 1.

Figure 3 is a vertical sectional view on the line 3, 3 of Figure 2.

Figure 4 is a vertical sectional view on the line 4, 4 of Figure 5 of a concrete beam that may be employed when a second story is added added to the building, Figure 1.

Figure 5 is a rear elevation of the beam Figure 4.

2

Figure 6 is a horizontal sectional view of an alternate form of panel that can be used in the building Figure 1, and also shows a corner column modification.

Figure 7 is a transverse vertical sectional view of the panel shown in Figure 6.

Referring to Figure 1 wherein is shown one corner of a one-story building embodying the invention, the numeral 10 denotes the foundation or base upon which the building rests, and this may be below ground with a portion 11 thereof extending above the grade line as usual.

Embedded at suitable intervals, say at every three feet, are the column supports indicated at 12, which may be pieces of ordinary pipe having a suitable inside diameter or bore and being of a suitable depth to receive the columns 13. If these are standard 2" pipe, the length of the supports 12 would be about 1 foot 2" and the bore of these supports would be sufficient to receive the 2" pipe with a little room to spare in order to permit a slight lateral movement of the pipe when the columns are forced downward, as hereinafter described.

25 The supports 12 can be embedded in the concrete foundation or each support may have a separate footing (by being set in a concrete block or the like) or they may be arranged in any other suitable manner that will hold them rigidly spaced apart in order to support the columns of the building.

If desired, the column supports may comprise suitable holes cored out in the foundation, or could be pins or tubular members extending upwardly therefrom, so that the column 13 would fit over these pins or tubes instead of into them. Such a modification is so obvious that it will not be shown and described in detail.

The columns 13 of the building may be made of standard 2" steel pipe which is strong enough for the average two story building, but it will be observed that a column of any suitable diameter, either round or of any other cross section may be employed.

45 Each column 13 is provided with a plurality of longitudinal slots 14 as best seen in Figure 3. These slots are spaced along the length of the column at any desired distance, and the slots are sufficiently long to permit the head portions 19 of the locking members 17 attached to the panels to enter these slots as presently described.

The wall panels that lie between the columns will now be described:

These may be of two types—that shown in connection with Figures 1-2 inclusive, or that shown in Figures 6 and 7.

Referring to Figure 1, the numeral 15 denotes a panel which may be made of concrete or the like. Preferably this is constructed as shown in Figure 2, where vertical sides of the panel are composed of cores 16 of relatively dense material such as concrete or the like, so that the arcuate column-engaging edges thereof can be shaped to fit around and embrace the columns 13.

The body of the panels as shown at 16a may be made of a lighter material than the vertical portions 16, such as lightweight concrete or any other material that can be pressed, cast, or otherwise formed into a panel.

Cast, or otherwise secured into the core 16, at suitable intervals along the vertical edges of each panel, are the locking members 17, each of which has a shank portion 18 embedded in the panel and extending outwardly therefrom and a head portion 19 which extends upwardly at an angle from the shank, in order to provide a tapered face 20 on each locking member.

The panels may be provided with diagonal reinforcing rods 21 cast therein, the ends of which project from the outer vertical edges of the cores 16 in order to form the projecting shanks 18 and head portions 19 of locking members as previously described.

Usually the diagonal reinforcements 21 are only employed on corner panels or slabs, but it will be understood that they may be employed in any of the panels, and that any suitable type of reinforcement may be employed, such as wire mesh or the like.

It will also be understood that the slabs or panels can be made of any suitable size to provide window openings, such as the panel 22, on which is placed the precast sill 23 above which is placed the metal window frame 24.

The metal window and door frames are made in such a manner that the vertical side members thereof are provided with slots 14 like those in the columns 13 and these side members may be covered by inner frame members 25 to provide a finish, and the space 31 between the members 25 and the columns 13 may be filled with concrete or some pourable material as hereinafter described in connection with the columns 13.

As an example of how the building may be erected, referring to Figure 1, the corner column 13a may be placed in its support 12, and then the panels 15a, 15b may be brought up against column 13a and the head portions 19 of the locking members of the panels are thrust through the slots 14 in the column. This brings the vertical edges of adjacent panels against the column which may then be driven downwardly, whereupon the ends 26 of the slots engage the tapered sides 20 of the head portions 19 of the locking members, and as the column is driven downwardly, the locking members are pulled inwardly by reason of the tapers 20, drawing the panels with them. This brings the abutting edges of the panels in close contact with the outer wall of the column 13.

A corner strip 27 may be used to close the outer gap between the outer edges of panels 15a and 15b, but it will be noted that strips are not necessary elsewhere between the edges of the panels. For example, the edge 28 of panel 15 is tight against the edge 29 of panel 15a which is likewise the case with all other similar joints in the building walls.

Before column 13a is driven downward, adjacent columns such as 13b or 13c are placed in position and the driving operation is performed

progressively, thereby locking the panels to the columns in a manner that will be obvious, the columns moving slightly in a lateral direction to permit this to be done.

The columns all having been driven downwards into the column supports 12, a suitable pourable material, such as concrete or the like, is poured down the bores 30 of the columns and into the spaces such as 31 in the window or door frames, and this material flows in and around the head portions 19 of the locking members, fills the slots 14, and, running down the bore of the columns, fills the spaces 32 below the columns in the supports 12; it rises in the space 33 between the inner wall of the supports 12 and the outer wall of columns 13, thus firmly locking the entire structure together.

If desired, mastic or similar waterproofing 34 is placed between the foundation and the bottom edges of the panels in order to prevent the ingress of moisture at this point. This waterproofing can also be applied to the top edges of the panel.

If a one story structure is to be erected, then metal plates 35 may be secured to the tops of the columns. A suitable light-weight channel, such as 36 is secured to the plates 35 in any suitable manner and the roof structure is attached to the channel 36 in any suitable manner.

It will now be seen that the metal framework comprising the channel 36 and supporting columns 13 carry all of the weight of the roof; or, in the case of a 2 story building, will carry the weight of the 2nd story, and that the panels 15 merely serve as enclosures, and do not carry anything except their own weight. The adjacent edges of the panels fit tightly around the columns and are rigidly and permanently secured thereto.

Obviously, the columns can be coated with mastic or similar waterproofing material before the panels are pulled thereagainst in order to provide the ingress of moisture at the joints between the panels and columns.

Obviously, any interior finish such as plaster as indicated at 37 in Figure 2 may be applied to the interior surfaces of the panels, and any exterior finish, such as stucco, shown at 38 may be applied to the exterior surfaces thereof.

In the event that it is desired to erect a 2nd story on the structure shown in Figure 1, the plates 35 are omitted and, referring to Figure 4, a collar 39 is welded or otherwise secured to the upper projecting ends of the columns 13.

A precast beam 40 is provided which has securely cast therein sleeves 41, adapted to fit over the upper ends of the columns 13. The sleeves come to rest on the collars 39, so that the weight of the beam is carried entirely by the columns 13 and is not transmitted to the panels or slabs 15 below the beams.

The beams have a rearwardly extending portion 42 for supporting the floor joists 43, which support the flooring 44. With the beams 40 in place at the top of the structure shown in Figure 1, it will be observed that the sleeves 41 now form a series of column supports similar to those shown at 12 and previously described, and therefore are adapted to receive the 2nd story columns, such as 46, which are in all respects similar to columns 13 and which in turn, are engaged by, and securely locked to panels 47, which form the 2nd story walls, said panels

being in all respects similar to those shown at 15.

It will be seen that when the columns 46 are driven downwardly that the bottom edges 45 thereof, will rest upon and be supported by the upper edge 48 of the columns 13, so that all the weight of the beams 40, columns 46, panels 47, and any roofing structure that may be carried on a horizontal channel, such as 36, secured across the upper ends of columns 46, will be supported by the lower framework composed of the columns 13 and their supports 12.

It will be understood that the upper columns 46 have their interior bores 49 filled with concrete or other similar material, such as described in connection with interiors 30 of column 13.

The beam 40 may, of course, have reinforcements of any suitable description, such as the rods indicated in dotted lines at 50 in Figures 4 and 5.

It will be obvious that the beam 40 may be cast as an L-shaped member to form a corner and to have 3 or more sleeves therein. For example, sleeves to receive the upper ends of columns 13a, 13b, and 13c in Figure 1, or two sections or more can be joined in any suitable manner such as by the metal plate 51 secured by bolts 52, embedded in the beams.

Referring to Figures 6 and 7, in order to form a panel construction as shown, wherein a membrane is employed, here the locking members 17' are the same as heretofore described, except that one of each pair is embedded in one side slab of the panel, such as the side 53, while the other member of the pair is embedded in the other side of the panel 54.

The slabs 53—54 are cored out as indicated at 55—56, so that when the slabs are placed together to form a panel, each panel is, in effect, a hollow shell, in which a dead air space or spaces exist.

To break up conduction and convection in the hollow space or spaces within the panel, a membrane 57 is provided, made of felt, roofing paper, or the like, and preferably impervious to moisture and fire-proof. Metal foil, or any other material, may be used.

Preferably two layers of this material are used and the ends of the layers shown at 58—59 in Figure 6 extend outwardly all around the panel, so that they may be folded around the columns 13 to form a substantially moisture-proof joint between the columns and panels.

At the bottom and top of each panel the membranes can be turned outwardly to form a moisture-proof joint as best seen in Figure 7, which shows the foot of one of the panels equipped with the membranes 58—59 resting upon the foundation 11. Each side 53—54 of the panel just described, may be equipped with any suitable form of reinforcement, such as the wire mesh reinforcement shown at 60.

The slabs 53—54 are laid against the membrane or membranes 57 which is given a light coat of mastic or suitable material that will adhere to the slabs and hold them together until the panels can be erected. But obviously, if desired, the slabs can be secured together by bolts or screws or in any other suitable manner.

The locking members 17' are shown in Figure 6 as embedded directly in the main body of the slabs forming the panel as distinguished from the arrangement shown in Figures 2 and 3 where the members 17 are embedded in the cores 16

forming the vertical edges of the panels. Either arrangement can be used, depending upon the nature of the material from which the body of the panel is formed.

When the panels shown in Figure 6 are assembled to the columns, it will be seen that the locking members 17' not only draw the panels to the columns as previously described, but that they also tend to draw the individual slabs 53, 54 towards each other to tightly grip and hold the membrane 57 therebetween.

If the edges of panel having the overlying membrane are given a light coat of mastic or other bituminous material before erecting the panels between the columns, each panel is, in effect, a sealed unit. In the event of a break-through through the outer wall of a panel—for example, a break through the slab 54 that would permit water to enter the cavity 56—as this cavity 56 is completely sealed off not only from the adjacent cavity 55 in the same panel by reason of the presence of the membrane 57, and also from all other like cavities and all other panels throughout the building, the moisture is confined to a comparatively small area of the broken panel.

Thus air circulation, conduction and convection in the walls is reduced to a minimum, and if the membrane 57 is water-proof, penetration of moisture from the outside of the building is prevented, and yet the form of construction is such that these added advantages are secured (and, compared with other forms of construction, without additional cost), without the necessity of the employment of skilled labor to attain them.

In the case of prefabricated buildings, the supports 12, columns 13 and panels 15 can be made to standard sizes, proper provision being made for standard window and door frames, with the result that a building can be erected with practically no cutting and fitting on the job, and by unskilled labor, and that the resultant structure will possess the advantages herein set forth.

Figure 6 illustrates a form of corner construction that may be employed to advantage in the type of building described. Here, two columns 13 are mounted upon the foundation as previously described, and a corner post 61 of molded material such as concrete or the like, is provided with the locking members 17' and is attached to the two columns as previously described. The adjacent panels are then brought against post 61 as shown. The columns 13 are driven downward, thereby locking the slabs and the corner post 61 to the columns in the manner previously described.

It will also be obvious that the membrane, being within the slab, is protected from mechanical damage in shipment and during erection.

If desired, suitable reinforcement rods, as commonly used in concrete building construction can be placed inside the columns 13 in order to strengthen the structure, the columns then being filled with cement grout or the like.

In the case of a two story structure, the first story frame-work can be erected as previously described, and the columns and panels locked together by pushing the columns downward into the supports 12 and the whole frame-work can be shifted laterally to the degree permitted by the fact that, as previously stated, the bore of the supports 12 is larger than the columns 13 therein.

The first story framework having been set up and the panel and columns having been locked

together, as previously described, the cement grout may be poured into the columns so that they are securely locked in the supports 12 and the grout is poured into the column to fill them only part way to the top. Short reinforcement rods are then placed within the second story columns 46 so as to span the joint between the lower end of columns 46 and the upper end of columns 13 and then the columns 46 are filled with cement as previously described.

It will be understood that the inside diameter of the sleeves 41 may be larger than the outside diameter of the columns 13 and 46 in order to permit lateral movement of these columns during the adjustment of the columns to the panels as previously described in connection with supports 12 and columns 13. The collars 39 are made large enough to close the annular space at the bottom of the sleeves 41 regardless of their diameter and the bottoms of columns 46 can, if necessary, have cut-away portions as shown at 61 to permit the grout to flow into space 62 about the columns 46 and 13 to position same in the sleeve 41. A perforated plate (not shown) can be put over the upper end 48 of column 13 to act as a foot for the lower end 45 of column 46.

It will be observed that if the first story columns are grouted and then the second story columns are erected thereon and the second story panels are placed in position, that the second story walls so erected can be laterally adjusted to close all joints before pouring the grouting into the second story columns. Thus the walls can be erected without trimming the panels to fit fixed spaces between the columns and a minimum of labor is required to erect the building.

What is claimed is:

1. A building construction including a foundation, equi-spaced upwardly extending openings in the foundation, vertical hollow columns one end of which is received in said openings and initially slidably mounted therein, a plurality of apertures in the columns, panels between the columns, reinforcing elements within the panels and extending beyond the vertical edges thereof, the ends of the reinforcing elements being bent upwardly to form hook-like members,

the hook-like members entering the apertures in the columns with the hook ends extending upwardly and away from the inner wall of the columns, whereby when the hook members engage the columns and the columns are forced downwardly into the openings in the foundation, the panels will be drawn toward said columns thus forming a wall of the building.

2. A construction as claimed in claim 1 where-
10 in the reinforcing members extend through the panel with the ends protruding beyond each of the vertical edges, said protruding ends being bent to form the hook-like members.

3. A construction as claimed in claim 1 where-
15 in the hook-like members are secured within the column and the column secured within the opening of the foundation by filling the column with a pourable and settable material.
